UNITED STATES PATENT OFFICE.

ABIJAH S. PARKER, OF CINCINNATI, OHIO.

CARRIAGE-CURTAIN KNOB-PATCH FASTENER.

SPECIFICATION forming part of Letters Patent No. 274,137, dated March 20, 1883.

Application filed July 20, 1882. (No model.)

To all whom it may concern:

Be it known that I, A. S. PARKER, a citizen of the United States, residing at Cincinnati, Hamilton county, Ohio, have invented a certain new and useful Improvement in Knob-Patch Fasteners for Carriage-Curtains, of which the following is a full, clear, and exact description.

My invention consists in fastening a knob-patch by means of a single metallic rim provided with teeth or prongs to pass through the curtain and patch, and bent down to clasp the patch, so as to secure it firmly without stitching, and to prevent tearing, without any secondary rim.

Figure 1 shows a section of the metallic rim and prongs; Fig. 2, a section of the rim, curtain, and knob-patch before the prongs have been bent down. Fig. 3 is a similar section with the prongs bent down over the patch. Fig. 4 is a rear view of the knob-patch fastened to the curtain.

A is the metallic rim, which may be made either round or oblong, or any suitable shape. 25 a b a b are the prongs on the under or rear side of the rim, usually struck out of the same sheet metal of which the rim A is made, and capable of being bent over. The prongs a a are on the outside of the rim, and do not 30 pass through the knob-patch, but only the curtain. b b are on the inner part of the rim, and pass through both the curtain and knob-patch. B is a portion of the curtain or fabric to which the knob-patch is to be fastened. C is the 35 knob-patch.

The rim A being constructed as described, small slits are made in the curtain for the passage of the prongs, through which they are inserted. The knob-patch C is then placed 40 against the curtain, on the opposite side from the rim, and within the circle formed by the

prongs a a, the prongs b b passing through slits or openings in the patch C, (or all prongs may pass through the patch, if desired.) The prongs a a are then bent down inwardly upon 45 the patch C, and the prongs b b are bent outwardly. These prongs hold the patch firmly and snugly to the curtain and prevent any tearing. The curtain and patch are both provided with an opening, K, and slit to serve as 50 a button-hole for the knob.

Knob-patches have heretofore been sewed to the curtain. By my invention all stitching is now done away with, and the patch is quickly, neatly, and firmly attached. If desirable, the 55 patch may be put on the other side of the curtain.

I am aware that curtain eye lids have been made by fastening a rubber button-hole between two rims of metal, which are clamped 60 together in a manner somewhat similar to my own, or by radial flanges of a metallic plate; but my invention does away with the use of one of these rims of metal, makes the fastening for the knob tighter and neater, and is 65 much more simple and inexpensive.

Having described my invention, I claim—

1. A knob-patch fastener consisting of a ring or rim of metal provided with prongs to pass through the curtain, and others which pass 70 through the curtain and the knob-patch, and all bent down to hold it securely to the curtain.

2. The metallic rim A, provided with the prongs a b a b, passing through the curtain B, 75 and embracing the patch on the front or rear side of the curtain.

A. S. PARKER.
